SHOE POLISHING DEVICE

Otto M. Dyer, Jr., Detroit, Mich.

Application April 19, 1957, Serial No. 653,809

2 Claims. (Cl. 15—32)

My invention relates to improvements in shoe polishing devices for use especially although not necessarily in the home, office or the like.

The primary object of my invention is to provide a shoe polishing device which may be operated by a foot of a person thereby obviating bending over and using and soiling the hands and which is of simple inexpensive construction and is economical to use.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a view in plan partly in horizontal section of a preferred embodiment of my shoe polisher;

Figure 2 is a view in vertical longitudinal section partly in side elevation;

Figure 3 is an enlarged view in front elevation with the cover removed;

Figure 4 is an enlarged view in vertical cross-section taken on the line 4—4 of Figure 2; and

Figure 5 is an enlarged fragmentary view in vertical section taken on the line 5—5 of Figure 3.

Referring to the drawings by numerals, the polisher of my invention comprises a generally rectangular platform 1 having reduced front and rear ends 3, 5 supported by front and rear axles 7, 9 having pairs of front and rear right and left ground wheels 11, 12, 13, 14 at the sides of the platform, the front wheels 11, 12 being grooved pulley wheels and fixed on the axle 7 for a purpose presently seen. The axles 7, 9 are journaled in bottom bearings 15, 17 on the platform and the rear wheels 13, 14 may be fixed or free on the rear axle 9 as desired. Suitable end thrust collars 21, 23 on the axles 7, 9 prevent end play of the axles 7, 9 in the bearings 15, 17.

A generally rectangular cover 25 fits around the edges of the platform, is suitable secured thereto by screws 27 and rises therefrom with a central, longitudinal top opening 29 therein for insertion into said cover onto the platform 1 of a foot of a person for polishing of a shoe by polishing means in said cover 25.

The polishing means comprises a pair of right and left side rotary brush units 31, 33 including a pair of parallel cylindrical brushes 35, 37 extending horizontally longitudinally over the platform 1 in parallel spaced relation at opposite sides of the longitudinal center of the platform 1 to receive a shoe therebetween and polish the sides thereof and which includes cores 39, 41 on forwardly extending shafts 43, 45.

A pair of larger diameter circular brushes 47, 49 on the cores 39, 41 at the rear ends of the brushes 35, 37 are provided to overlap in the rear of a shoe for polishing the heel end of a shoe. Slots 51, 52 in the platform 1 accommodate the disk brushes 47, 49.

For polishing the upper front toe portion of a shoe a horizontal, cylindrical brush 55 is provided comprising a horizontal, cylindrical brush 55 extending between the

2

brushes 35, 37 above and parallel therewith and which also includes a core 57 fast on a forwardly extending shaft 59. The brush unit 53 is provided for insertion under the brush 55 of the toe portion of a shoe and includes at its front end on the core 37 thereof a larger diameter circular brush 61 for positioning of the tip of a shoe thereagainst to polish the same.

The right and left side brush units 31, 33 are rotatably and vertically swingably mounted to polish the sides 10 and heel end of a shoe on a pair of right and left bifurcated, U-shaped right and left, yoke bars 63, 65 at the front end of the platform and in which the front ends of the shafts 43, 45 are journaled at intermediate portions of said bars 63, 65. The bars 63, 65 have free ends 67, 69 overlapping and pivoted on a horizontal stub-shaft 71 in the longitudinal center of the platform and said bars 63, 65 extend in V formation from said shaft 71 for vertical swinging thereon. Apertures 73 in the bars 63, 65 for selective insertion of the shaft 20 71 therein provide for adjusting the bars 63, 65 to vary the spacing between the right and left brush units according to the width of a shoe.

The shaft 71 extends horizontally forwardly from a supporting block 75 supported by screw bolts 77 rising 25 through the platform 1 for vertical screw feed adjustment of the block 75 and shaft 71 whereby to vary the height of the brush units 31, 33 from the platform 1.

The top brush unit 53 is mounted for swinging side-wise over the upper toe portion of a shoe by means of 30 a bar 79 like the bars 63, 65 upstanding from the shaft 71 with the shaft 59 of the top unit journaled in an intermediate portion thereof, said bar 79 being disposed between the ends 67 of the bar 63 and swingable transversely of the platform 1 to correspondingly swing the brush unit 53.

Means for spraying liquid shoe polish on the brushes 35, 37, 47, 49, 53 comprises a liquid polish containing bulb 81 suitably fixed on the rear end of the platform and a U-shaped suitably apertured spray pipe 83 extends forwardly from opposite ends of the bulb 81 over the brush units 31, 33 and the brush 55, for spraying polish downwardly by compression of the bulb by the heel portion of a shoe pressed against the bulb. A flexible filler tube 85 is provided on the bulb 81.

The brush units 31, 33, 53 are rotated in relatively reverse directions in response to movement of the platform 1 forwardly and rearwardly by a foot on the platform 1 to rotate the front wheels in unison counterclockwise and clockwise respectively and by the following means.

Pulleys 87, 89, 91 of like diameter are fixed on the shafts 43, 45, 59 in the yoke bars 63, 65, 79. Smaller idler pulleys 93, 95 are mounted in the yoke bars 63, 65 in substantial alignment with the right and left front wheels 11, 12 and a smaller idler pulley 97 is mounted in the yoke bar 79 over the pulley 91. A swiveled idler pulley 99 is mounted on the platform in line with the top of the right front wheel 11.

A cable 101 is wound at its end reversely around the right and left front wheels 11, 12 and terminally fastened thereto by extension through apertures, as at 103, in the said wheels and then secured by screws, as at 105 to said wheels. The cable is wound counterclockwise around the right front wheel 11 and clockwise around the left front wheel 12. Intermediate said wheels 11, 12 the cable 101 is trained under the idler pulley 99 and upwardly to the idler pulleys 93 and is looped around the idler pulley 93 and the pulley 87 on the yoke bar 63 and similarly looped around the idler pulley 95 and the pulley 89 on the yoke 65 to extend upwardly from the idler pulleys 93, 95 to the idler pulley 97 from opposite

3

sides thereof and around which and the pulley 91 said cable is looped.

cable is looped. In operating the device a person inserts his or her foot through the opening 29 onto the platform 1 between the brushes 35, 37 of the right and left brush units 31, 5 33 with the toe portion of the shoe under the brush 55 of the top brush unit 53 and slides the foot backwardly on the platform 1 to compress the bulb 81 so that a desired quantity of shoe polish is sprayed onto the brushes after which the foot is slid forwardly to release 10 said bulb.

The apparatus is then moved forwardly and backwardly by foot pressure to rotate the front wheels 11, 12 forwardly and backwardly whereby said wheels alternately wind up the cable 101 and exert pull thereon alternately in opposite directions thus causing the brush units 31, 33, 53 to rotate in one direction and then in the opposite direction. During this operation the frictional engagement of the brushes 35, 37, 55 with the sides and top of the shoe causes said brushes 35, 37 to ride up or down depending on the direction of rotation thereof and the brush 55 of the top unit 53 to move laterally in opposite directions over the top of the toe portion of the shoe depending on the direction of its rotation, this action of the brushes 35, 37, 55 swinging the yoke bars 63, 65 upwardly and downwardly and the yoke bar 79 from side to side. During this action of the yoke bars 63, 65, 79 the idlers 93, 95, 97 and the pulleys 87, 89, 91 roll in the loops of the cable 101. The foot may be moved back and forth on the platform 1 to engage the brushes 47, 49 and 61 for polishing the tip of the toe portion of the shoe and the heel end as desired.

Stop pins 169 may be provided on the block 73 to limit swinging of the yoke bars 63, 65, 79.

A raised longitudinal portion 111 may be provided on the platform to elevate a shoe between the brushes 35, 37 so that said brushes will polish the sides of the sole and heel.

As will now be manifest, the brushes of the device are driven by rolling contact of the ground wheels 11, 12 with the ground and movement of the entire device forwardly or rearwardly with the operator's foot in fixed position relative to the device, whereby the duration of rotation of the brushes is not limited by movement of the operator's foot relative to the device.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and

equivalents may be resorted to, falling within the scope of the invention as claimed.

What is claimed as new is as follows:

What is claimed as new:

1. A shoe polishing device comprising an elongated platform having front and rear ends, a pair of supporting ground wheels for the platform rotatably mounted thereon at opposite sides thereof and connected together for rotary travel in unison forwardly and rearwardly in response to forward and rearward movement of the platform by a foot positioned on the platform in the longitudinal center thereof with toe portion of a shoe on the foot facing forwardly, a pair of rotary cylindrical brushes above said platform extending parallel longitudinally thereof at opposite sides of said longitudinal center for engaging and polishing opposite sides of a shoe and having axial shafts, a pair of bars journaling said brushes for rotation in opposite directions respectively pivotally mounted on said platform for upward and downward swinging to permit said brushes to ride upwardly and downwardly on a shoe in response to rotation of the brushes in opposite directions in engagement with a shoe, and means drivingly connecting said wheels to said brushes to rotate the same in opposite directions in response to travel of the wheels forwardly and rearwardly, respectively comprising a pair of driven pulleys fast on said shafts respectively, a pair of idler pulleys on said bars spaced from the driven pulleys, and a cable trained around the idler pulleys and looped around the driven pulleys and terminally fixed to and wound in one direction around one ground wheel and in the opposite direction around the other ground wheel and whereby the brushes are rotated by rolling engagement of the ground wheels with the ground and movement of the entire device forwardly or rearwardly, bodily, with the operator's foot in fixed position relative to the device, so that duration of rotation of the brushes is not limited by movement of the operator's foot relative to the device.

40 2. The combination of claim 1, and a pair of larger diameter circular brushes on one end of the pair of cylindrical brushes and rotatable thereby in overlapping relation to the heel portion of a shoe to polish said portion.
